(57) **CLAIM**

The ornamental design for a sampling and testing device, as shown and described.

DESCRIPTION

FIG. 1 is a perspective view of a sampling and testing device in an open position in accordance with the present invention. FIG. 2 is a right side view of the sampling and testing device of FIG. 1 in an open position in accordance with the present invention.

FIG. 3 is a left side view of the sampling and testing device of FIG. 1 in an open position in accordance with the present invention.

FIG. 4 is a top view of the sampling and testing device of FIG. 1 in an open position in accordance with the present invention.

FIG. 5 is a bottom view of the sampling and testing device of FIG. 1 in an open position in accordance with the present invention.

FIG. 6 is a rear view of the sampling and testing device of FIG. 1 in an open position in accordance with the present invention.

FIG. 7 is a front view of the sampling and testing device of FIG. 1 in an open position in accordance with the present invention.

FIG. 8 is a perspective view of the sampling and testing device of FIG. 1 in a closed position in accordance with the present invention.

FIG. 9 is a right side view of the sampling and testing device of FIG. 8 in a closed position in accordance with the present invention.

FIG. 10 is a left side view of the sampling and testing device of FIG. 8 in a closed position in accordance with the present invention.

FIG. 11 is a top view of the sampling and testing device of FIG. 8 in a closed position in accordance with the present invention.

FIG. 12 is a bottom view of the sampling and testing device of FIG. 8 in a closed position in accordance with the present invention.

FIG. 13 is a rear view of the sampling and testing device of FIG. 8 in a closed position in accordance with the present invention; and,

FIG. 14 is a front view of the sampling and testing device of FIG. 8 in a closed position in accordance with the present invention.
